UNITED STATES PATENT OFFICE

108,702

DESIGN FOR A PACKAGE OPENER

Martin M. Monaghan, Wellsburg, W. Va.

Application June 8, 1937, Serial No. 69,732

Term of patent 3½ years

To all whom it may concern:

Be it known that I, Martin M. Monaghan, a citizen of the United States, residing at Wellsburg, in the county of Brooke and State of West Virginia, have invented a new, original, and ornamental Design for a Package Opener, of which the following is a specification, reference being had to the accompanying drawing, forming part thereof.

I claim:—

The ornamental design for a package opener as shown.

MARTIN M. MONAGHAN.
